DESIGN FOR CARPET.

Specification forming part of Design No. 6,588, dated April 15, 1873; application filed April 8, 1873.

To all whom it may concern:

Be it known that I, ALFRED HEALD, of Philadelphia, county of Philadelphia and State of Pennsylvania, have invented a Design for Carpet-Pattern, of which the following is a specification:

The figure in the accompanying drawing clearly represents my design for a carpet-pattern, the principal features of which are the bands A, B, and C, crossing each other at right angles and inclosing square or diamond shaped figures D. Each of the bands A, B, and C has upon both sides an ornamental edging, a, and the interior is occupied by foliated ornamentation, all of a character too clearly shown in the drawing to need description.

The edgings *a* of the bands inclose and form the borders of the square or diamond shaped figures D, each of the latter having a central ornament, *c*, surrounded by four corner ornaments, *d*, composed of small dots, as shown.

Irrespective of the colors employed, I claim—

The design for a carpet-pattern, substantially as described, and as represented in and by the accompanying drawing.

In testimony whereof I have signed my name to this specification in the presence of two subscribing witnesses.

ALFRED HEALD.
